UNITED STATES PATENT OFFICE.

WILLIAM HENRY WAKER, OF SOUTH NORWOOD, ENGLAND, ASSIGNOR OF ONE-HALF
TO SAMUEL PECK, OF WALLINGTON, ENGLAND.

PERCUSSIVE HAMMER, DRILL, AND THE LIKE.

1,116,519.

Specification of Letters Patent.

Patented Nov. 10, 1914.

Original application filed June 16, 1913, Serial No. 773,993. Divided and this application filed February 14, 1914. Serial No. 818,691.

To all whom it may concern:

Be it known that I, WILLIAM HENRY WAKER, a subject of the King of Great Britain, and resident of 67 Whitworth road, South Norwood, in the county of Surrey, England, have invented new and useful Improvements in and Connected with Percussive Hammers, Drills, and the like, of which the following is a specification, being a division of my application Serial No. 773,993, filed June 16, 1913.

This invention relates to improvements in and connected with percussive hammers, drills and the like and chiefly concerns that type of percussive tool in which the rod portion of the piston hammer is suitably formed to coöperate with a nut device to produce rotation of the latter during the travel of the piston in one direction the rotation being imparted to a tool-holding or chuck sleeve by means of a suitable engagement between the nut sleeve and chuck sleeve, or between the piston and chuck sleeve, and reverse rotation of the nut being prevented by means of a ratchet and pawl mechanism.

According to this invention the piston is double-ended, that is to say each end of the piston has its respective rod portion, so that the piston has a rod portion not only at the front end but also at the rear end. Therefore, when one rod portion becomes worn by use as a hammer head, the piston may be removed and reversed or turned end for end, so that the opposite rod portion will be brought into use as a hammer head.

An important development consists in providing a nut sleeve and ratchet and pawl mechanism which can be readily applied to either end of the cylinder of the tool, so that when the piston is reversed end for end, the nut sleeve and ratchet and pawl mechanism can be transferred to the rear end of the cylinder.

Ratchet and pawl mechanisms may be fitted on both ends of the tool and two interchangeable nut sleeves may be employed in connection therewith, one being arranged at the front and one at the rear. If, therefore, the forward piston rod portion be provided with helical devices running in one direction and the rear piston rod portion be provided with helical devices running in the opposite direction the employment of

one nut only at the forward end will give 55 one speed of rotation and the employment of both nuts at respective ends will produce higher speed of rotation of the drill. One piston rod portion, however, may be helically formed for coöperating with a rifled 60 nut, while the other piston rod portion is without helical devices and may be square or angular in cross section, or fluted or otherwise suitably formed so that it cannot turn in a sleeve which may be similar externally to the rifled nut but which is formed with a non-helical square or angular or fluted bore to correspond with its respective rod portion. This sleeve may be conveniently referred to as a nut sleeve although 70 it does not produce rotation after the manner of a nut proper. With this arrangement a positive drive or turning moment is produced, because the piston when urged in one direction is positively held against rotation by the square, angular or fluted rod 75 moving in the appropriate so-called nut, which latter in turn is held against rotation in one direction by its appropriate ratchet and pawl mechanism. Consequently the 80 rifled nut is positively forced to turn and imparts its turning movement to the chuck sleeve and the tool steel in the latter. By simply removing the pawls of the ratchet and pawl mechanism belonging to the 85 square or rifled nut, the turning effort is no longer positive, the rotation being then due to the reluctance of the heavy piston to turn under the action of the rifling, the nut sleeve and chuck being consequently given 90 what is termed a slip drive or rotation. The ratchet and pawl mechanism may be reversible as set forth in my application for United States Patent Serial No. 773,993 filed June 16th 1913.

In order to enable the invention to be readily understood reference is made to the accompanying drawings in which:—

Figure 1 is a longitudinal section of a percussive drill in which a double ended piston is employed according to this invention; Fig. 2 is partly a plan of Fig. 1 and partly a section on the line II—II Fig. 1; Fig. 3 is a section on the line III—III Fig. 1; Fig. 4 is a section on the line IV—IV 105 Fig. 1; Fig. 5 is a longitudinal section of a modified form of percussive tool the section being taken in a plane at right angles

to the plane of the section Fig. 1; Fig. 6 is a sectional elevation of a modified form of hammer piston; Figs. 7 and 8 are views of further modified forms of hammer pistons.

Referring to the drawings the cylinder *a* consists of a tubular part suitably flanged in a similar manner at both ends and containing a piston *b* which is double ended, that is to say, it is formed with forward and rearward portions *c* which may be identical in every respect, or one portion may have a right-handed helical formation and the other a left-handed helical formation. Or one rod portion might be formed with a left or right handed helix and the other portion might be fluted, or square in cross section, or plain, or otherwise suitably formed, but in any case, the parts are so constructed that the piston may be taken out of the cylinder and reversed or turned end for end and then reinserted. In this way when one rod portion *c* becomes worn by reason of its action as a hammer head, the reversal of the piston brings the other rod portion into action as the hammer head, without affecting the working of the apparatus, as will be explained. The rods are shown formed with axial passages 17 communicating with radial passages 16 formed at their inner ends for permitting of the escape of some of the pressure fluid from the interior of the cylinder to a hollow drill shank when used but naturally the passages 16 and 17 may be omitted from either or both of the rod portions *c*. The rod portions need not be formed on the piston but if desired they may be separately formed and fitted to the piston. For example the rod portions may have tapered ends adapted to be inserted, and if desired secured, in corresponding bores or recesses in the piston as shown in Fig. 6.

The front rod portion *c* constantly engages a nut *e* during its reciprocation which nut is rifled or suitably formed for co-operating with the front rod portion *c* and the extremity of the front rod *c* acts as a hammer head and strikes against the extremity *f* of the shank *g* of the tool *h*.

The rear end of the cylinder is closed by a cover *j* which is furnished with two perforated lugs *n* to take longitudinal bolts *o* for securing the said cover *j* and the front head *p* on respective ends of the cylinder, the front head *p* being formed with similar lugs as shown in Fig. 2.

The front end of the cylinder is closed by a ring *g* formed with an annular shoulder *r* for supporting one end of a ratchet ring *s* hereinafter described. The ratchet ring *s* is formed on its interior with ratchet teeth *t* and engages the shoulder *r* of the cover ring *g* and also the shoulder *v* on the front head *p*. Therefore by tightening up the nuts *v* on the bolts *o* the front head *p* is drawn to-

ward the front end of the cylinder and clamps between itself and such front end the ratchet ring *s* and cover ring *g* aforesaid. At the same time the rear cover *j* is forced toward the rear end of the cylinder *a* and in this way the various parts *a j g* and *p* are held together rigidly.

The front sleeve nut *e* is mounted within the front ratchet ring *s* and front head *p* and is of reduced diameter at *w* for engaging a shoulder in the tool chuck sleeve *w*. The nut *e* is provided with radial recesses *y* containing sliding pawls *z* which are forced outward by helical springs *l*. The pawls may be formed with cylindrical shanks *z* which may be loosely inserted into the springs *l*. As indicated by chain lines in Fig. 1, the intermediate portion of the nut *e* is formed approximately square in cross section and fits easily within the square recess *z* in the enlarged rear end of the chuck *w*. The intermediate portion *z* of the bore of the chuck sleeve *w* is cylindrical. The bore *z* of the chuck is angular for receiving the correspondingly shaped shank *g* of the steel or tool *h*. The front head *p* entirely surrounds and shoulders against the chuck sleeve *w*. Thus the chuck sleeve *w* is held against the nut sleeve *e* and the latter is held against the cover ring *g*, a ball or anti-friction bearing *g* being preferably interposed between the sleeve *e* and the ring *g*. A buffer or packing ring *g* may be seated at the front end of the bore *z* and the end *f* of the shank *g* fits within the ring *g*.

During the rearward stroke for example of the piston *b* the pawls *z* will engage the ratchet teeth and prevent the nut *e* from rotating so that the piston and its rods will be forced to turn. On the forward stroke, however, the pawls will slip past the ratchet teeth, thereby allowing the rectilinear movement of the piston and its rod to produce a turning movement of the rifled nut *e* which, owing to the engagement of its square portion with the chuck sleeve *w*, will cause the latter to turn and revolve the tool. By removing the front head *p* and ratchet ring *s*, withdrawing the pawls *z* and re-inserting them in reverse positions, turning the ratchet ring end for end and replacing it in position and finally re-applying the front head and securing the same by the bolts *o* and nuts *v*, the apparatus will be in a condition for producing reverse revolution of the tool steel during the rearward stroke of the piston.

Lugs *o* may be provided on the rear cover *j* and the handle *19*, *19*^a may be secured thereto by short eye bolts *21*. It is advantageous to arrange buffers *22* on each side of the lugs *o* in order to minimize the effect of shock and vibration upon the operator.

The rear cover *j* is cupped or recessed in

the axial direction to receive the rear rod portion *c* and is shouldered interiorly so as to accommodate a rear nut *e* which is preferably of the same external shape as the forward nut *e*. A rear cover ring *q* and a rear ratchet ring *s*, which are counterparts of the front cover ring *q* and front ratchet ring *s* respectively, are also preferably employed so that any of the parts on the rear end are interchangeable with similar parts on the front end. This is not only very advantageous in the case of the piston rods differing from one another in character as indicated above, but in the case of the two rod portions being similarly formed, so that either one of the rod portions *c* will coöperate with either of the nuts *e*, only one set of spare parts need be provided, or carried, which spare parts will be capable of being applied to either the front or rear end as desired. The ratchet rings *s* may be formed with lugs or dowels to engage the adjacent parts for the purpose of preventing the rings *s* from turning.

25 The nut sleeve *e* shown in Fig. 3 is formed with four radial recesses, and pawls *z* may be inserted in only two opposite recesses if desired, or four pawls may be used if the conditions render the employment of additional pawls desirable. Moreover the four recesses enable a pair of pawls to be changed from one pair of recesses to another pair.

It may be observed that the rear ratchet ring *s* may be taken off and turned end for end and the pawls in the rear nut *e* may be reversed in their recesses in exactly the same manner as above described with reference to the front nut and ratchet ring. It will be noted that in Fig. 1 the greatest interior diameter of the cover *j* is sufficiently large for enabling the square exterior portion of the rear nut *e* to turn therein. It is preferred to arrange a lubricant receptacle of some kind at the rear end of the tool.

45 In the event of one rod portion *c* being formed with helical devices and the other rod portion being formed as a plain cylindrical rod *c*¹² as shown in Fig. 7, the rotation due to the coöperation of the nut with the helical devices will not be positive but will be what is called a slip rotation. Supposing the piston to be introduced into its cylinder with the helically formed rod to the front and the plain cylindrical rod to the rear, it will be readily understood that by suitably arranging the ratchet ring *s* on the front and the pawls *z* in the front rotation nut *e*, the turning movement may be produced either during the forward or rearward stroke of the piston as explained above. If desired a suitable sleeve *c*¹² shaped externally like the nuts *e* may be inserted in the rear end of the cylinder, in place of the rear nut *e* seen in Fig. 1, for the plain cylindrical rod portion to work in.

This arrangement would allow of reversal of the piston end for end in order to make the plain cylindrical rod act as the hammer. This, of course, would necessitate changing over the front nut *e* to the rear end of the cylinder, and the sleeve *c*¹² aforesaid to the front end. With the parts in the new position it would be necessary to turn the tool by hand in order to turn the drill, owing to the rotation nut being at the rear end and having no operative connection with the drill steel. The latter however being engaged with the chuck sleeve *x* which in turn is engaged with the square exterior of the sleeve which has a similar exterior to the rifled nut sleeves, and the pawls *z* in the said non-rifled sleeve engaging in one direction or the other with the ratchet ring *s*, enables the drill steel to be turned in one direction or the other by a turning motion imparted to the body of the tool by means of the handle thereof.

If one rod portion is made square or angular in cross section as at *c*¹³ Fig. 8 while the other rod portion is helically formed and the two nut sleeves *e* are made with similar exteriors but with bores corresponding with the respective rod portions, the sleeve *c*¹⁴ having an angular bore, then a positive rotation will be secured. Moreover it will be possible to secure such positive rotation either during the forward stroke, or during the rearward stroke, whether the helical rod portion and its rifled nut are arranged at the front end or at the rear end as will be readily understood.

In many cases it will be advantageous to form a right handed helix on one rod portion and a left handed helix on the other rod portion. Thus, if in this case only the front end rotation nut *e* is employed, an ordinary speed slip rotation is produced, but if the second rotation nut *e* be inserted at the rear end, a positive rotation at double speed will be secured which may be very advantageous when working in soft material. Of course, the speed of rotation instead of being doubled may be suitably increased by choosing for the helix on one rod portion a pitch which is different from the pitch of the helix on the other rod portion. In the latter case there will be obviously three possible rotation speeds, one being obtainable by having one nut sleeve on the front end, a second being obtainable by reversing the piston and arranging the other nut sleeve on the front end and the third speed being obtainable by employing both rotation nut sleeves as indicated above. With the arrangement last named it is advisable to provide a ball bearing *6* at the rear end, as shown in Fig. 1; in addition to and similar to the ball bearing at the front end.

It will be seen, therefore, that by provid-

ing interchangeable and reversible parts as hereinbefore indicated, the modes of using the drill and the effects obtained can be varied in many ways without any complication being introduced into the apparatus and with great advantage as regards exchanging, replacing or interchanging parts, for the purpose of renewing or repairing the same or for dealing with varying conditions.

10 The change from a slow speed rotation drill to a high speed, or vice versa, or from a drill having right hand rotation to a drill having left hand rotation, either at high speed or slow speed, and having rotation 15 during either the forward or rearward stroke, is capable of being effected in a simple and easy fashion and within a very short space of time. If desired, the handle 19 of the tool illustrated in Fig. 1 may be formed 20 with extensions 23, as shown in that figure, in order to allow of a more powerful leverage being obtained in manipulating the tool.

The valve device and the arrangement of ports and passages are not described herein 25 for the reason that they are not concerned with the subject matter of the present application but form the subject of my application Serial No. 818692, filed February 14, 1914.

30 In the modification seen in Fig. 5 the buffer ring 9 and the ball bearings are omitted and the nut sleeve *e* is slightly modified. The recesses in the nut sleeve *e* are formed at the bottom with sockets 56 which receive 35 and guide the stems 3 of the pawls *a* while the springs 1 are seated alongside the sockets 56.

It will be understood that the helical devices or helical formations for the piston rod 40 portions hereinbefore referred to may take any of the known forms for producing rotation. Likewise the rod portions which are formed with axially directed devices merely for preventing relative rotation while allowing of sliding engagement between such rod portions and their respective sleeves may be otherwise suitably formed to produce a rectilinear guiding engagement.

I claim:

50 1. A percussive hammer, drill, or like tool, comprising a piston, a rod portion on each end thereof, a rotation nut adapted to work with one of said rod portions, ratchet and pawl mechanism operatively connected with 55 said nut the construction and arrangement being such that the piston is capable of being reversed end for end in the cylinder so that either rod portion may be used as the hammer head.

2. A percussive hammer, drill, or like tool, 60 comprising a piston having a rod portion on each end and capable of being reversed end for end in its cylinder so that either rod portion may be used as the hammer head, interchangeable nuts adapted to coöperate 65 with the respective rod portions, and ratchet and pawl mechanism adapted to coöperate with the nuts substantially as described.

3. A percussive hammer, drill, or like tool, 70 comprising a piston having a rod portion on each end and capable of being reversed end for end in its cylinder so that either rod portion may be used as the hammer head, said rod portions having dissimilar formations, 75 rotation nuts corresponding with respective rod portions and adapted to be applied to both ends of the cylinder and to be interchangeably arranged therein, and ratchet and pawl mechanisms in coöperative relation with the nuts substantially as described. 80

4. A percussive hammer, drill, or like tool comprising in combination a piston having a rod on each end, helical devices on said rods, rotation nuts engaging respective rods, 85 pawls removably mounted in said nuts, and ratchet rings adapted to engage said pawls substantially as set forth.

5. A percussive hammer, drill, or like tool comprising in combination a piston having a rod on each end, helical devices on said rods, rotation nuts engaging respective rods, 90 reversible pawls mounted in recesses in said nuts, and reversible ratchet rings adapted to engage respective sets of said pawls substantially as set forth. 95

6. A percussive hammer, drill or like tool comprising in combination a piston, a rod on each end of said piston, helical devices having a pitch of one value on one of said rods, 100 helical devices having a pitch of a different value on the other of said rods, rifled nuts adapted to coöperate with respective rods, and ratchet and pawl mechanisms adapted to coöperate with respective rifled nuts substantially as set forth. 105

7. A percussive hammer drill or like tool comprising in combination a piston, a rod on each end of said piston, helical devices on said rods, a rifled nut adapted to coöperate with either of said rods and reversible ratchet and pawl mechanism adapted to coöperate with said rifled nut substantially as set forth. 110
